The ornamental design for a charging base for electronic hair curling device, as shown and described.

DESCRIPTION

FIG. 1 is a front perspective view of a charging base for electronic hair curling device showing our new design; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a perspective view showing the charging base for electronic hair curling device relative to an example of an electronic hair curling device.

The broken lines shown in the drawings illustrate portions of a charging base for electronic hair curling device that form no part of the claimed design. The dot-dash broken lines shown in FIGS. 1-2 and 4-7 depict the bounds of the claim and form no part of the claimed design.
